UNITED STATES PATENT OFFICE

ALBERT E. DERUS, OF CHICAGO, ILLINOIS

MECHANICALLY-OPERATED FIGURE TOY

Application filed May 12, 1926, Serial No. 108,614. Renewed March 22, 1930.

This invention relates to coin-operated vending machines of the type employed for dispensing packaged candies, chewing gum, lozenges and like products, and its object is 5 to provide a machine of this kind which furnishes entertainment of a novel character during its operation.

A further object of the invention is to combine with a vending machine of the above 10 type a realistic songbird scene, wherein birds execute musical and bodily movements true to life.

A still further object of the invention is to provide a novel mechanism which co-ordinates the musical and bodily movements of 15 each performer in simulation of the actual movements executed by the living birds when in song.

Another object of the invention is to so design the mechanism last referred to as to be 20 capable of easy replacement to vary a given performance if desired, that is, to change the arrangement and pitch of the musical notes and the sequence and duration of the bodily 25 movements of the performers.

A final but nevertheless important object 30 of the invention is to construct the novel machine of few parts and to operate efficiently, so that it may require a minimum amount of attention.

With the above objects in view, and any 35 others which may suggest themselves from the specification and claim to follow, a better understanding of the invention may be had by reference to the accompanying drawings, in which

Figure 1 is a front elevation of the novel machine;

40 Fig. 2 is a view of the interior thereof when the right-hand wall in Figure 1 has been removed;

Fig. 3 is a plan-section of the mechanism in the lower part of the machine;

45 Fig. 4 is a laterally-expanded view of the performance-control unit;

Fig. 5 is an elevation of the mechanism shown in Figure 3, as viewed on the section line 5—5 of that figure;

50 Fig. 6 is a partly cut-away perspective view

of the mechanism at the upper part of the machine;

Fig. 7 is a sectional view of a songbird specimen, taken from the reversed side of a 55 similar showing in Figure 6;

Fig. 8 is a detail section of a timing mechanism, taken on line 8—8 of Figure 3;

Fig. 9 is a section on the line 9—9 of Figure 3 disclosing the interior of a bellows; and

Fig. 10 is a perspective view of a sound-producing element. 60

As illustrated in Figure 1, the machine is in the form of an ornate cabinet 15, the ornamental details of which are brought out more fully in my design Patent No. 69,500, dated February 23, 1926. The cabinet is of metal, and its visible features comprise a glass panel 16 through which the confection packets 17 are displayed, a coin-slot head 18, a door 19 adapted to be swung down for the removal of the packets, a door 20 with a lock 21 for access to the bottom of the machine when the coins are to be collected by the maintenance or servicing agency, and a glass dome 22 to protect the songbird specimens 23 while rendering them and their actions clearly visible to the public. 65

The machine entails seven units, namely, as follows: (1) a vending apparatus; (2) a spring motor; (3) a coin-operated motor actuator; (4) an automatic stop for the motor; (5) a motor-operated bellows; (6) a sounding tube; and (7) a synchronized mechanism to operate the sounding tube and induce the bodily movements of the performers, these units co-operating to produce the musical and bodily effects evident to the observer or patron. 75

The spring motor is indicated at 24 and is of any suitable type, originating with a key spindle and pinion 25 for winding and involving a multiplying gearing, which terminates in a flywheel 26 carried by a spindle 27. The motor is disposed in a clockwork 80 frame 28, and the latter is suitably attached to or formed as a part of the base 29 of the vending apparatus. 85

The mechanism units above enumerated 90 are carried by or suspended from the top 30 100

of the cabinet, so that they may be removed for inspection or repairs by merely raising the said top until the mechanism is clear of the casing. Where the machine is exposed to tampering, it will be advisable to secure the mechanism body to the cabinet by a suitable lock, such a measure also preventing unauthorized access to the accumulated coins by the removal of the mechanism.

The vending apparatus originates with the coin-slot head 18, in which the different slots represent varieties of the confection dispensed. For handy selection and compactness, the slots 31 are grouped closely, but the coin chutes 32^a leading therefrom are gradually separated along their downward course for better individual application to other parts as well as for better access in the event of installation or attention. In front of the coin chutes is a series of laterally-grouped compartments 33 in which are stacked rolls 17 of the peppermints, fruit drops, lozenges or other commodity vended, as indicated by dotted lines in Figures 3 and 9. These are fed downwardly upon a platform 35 to which access is handy when the door 19 is swung open, whereby to remove a given packet. The feeding from the compartments is effected by a free arrangement of spools 36 in succession on a rod, the spools being arranged at the bottoms of the respective compartments and independently rotatable. The spools have near the ends spiders 37 between whose arms a seat is formed for each lowermost roll or packet 34, as clearly indicated in Figure 9. It will be evident in this figure that each counter-clockwise quarter-turn of a spool will cause the release of the lowermost roll 34, the next roll in turn finding a support in the succeeding hollow of the spool spiders. The spool assembly is disposed in a wall 38 erected upon the base 29 and being braced at 39^a thereto; and this wall is slotted at 40 at the sites of the spool spiders 37 to permit them to operate in front for the feeding of the rolls 34—as just explained—and at the rear subject to individual controls to be presently described.

Referring more particularly to Figures 3 and 5, it will be noted that each coin chute 32 is cut near its lower end with a notch 41 at one side. In this notch is adapted to seat the bend 42 of a lever 43 pivotally supported in a bearing standard 44 erected on the base 29. From the rear end of the standard a lever projects in the form of a crank 45. Springs 46 carried by the base 29 are urged against the cranks 45 in a direction to so rock the levers 43 that their bends 42 will seat in the upper ends of the respective chute notches 41, as shown. The levers will also—in this position—impede the movement of the spools 36 in the dispensing direction previously described, by blocking the lower leg of one

spider of each spool, it being understood that the spiders and shank of a given spool are in one unit or body. At this stage it will follow that when a coin drops down in a given coin chute 32, the force of its descent will depress the lever 43 to clear the bottom spider leg, in which event the weight of the corresponding roll or stack of rolls 34 will cause the spool to turn and dispense the lowermost roll. In the meantime the swift passage of the coin results in the summary release of the lever 43, whereby it is restored to its original position—by the pressure of the respective spring 46—so as to again block the spool spider and prevent a further dispensing action.

On the subject of the vending apparatus, a safeguard against a smaller—that is, less valuable—coin used with fraudulent intent, is illustrated in Figure 6. A short distance below the top 30 of the cabinet the wings or flanges 47 of the coin chutes 32 are notched as indicated at 48. The spacing of each set of notches is short of the diameter of the proper coin, but greater than that of a smaller coin. Between each set of notches a strip 49 is struck back from the front wall of the chute with a tendency to urge a descending coin rearwardly by way of the notch spacing referred to. The strip 49 is of resilient material and yields when the full-sized coin descends, so that the latter continues down the chute; however, in the case of the smaller coin, it will be deflected by the strip 49 and cast out of the chute by way of the notch spacing, to fall into a suitable receptacle 50 and therefore fail to produce the intended result. For the proper amount of resiliency, the strip 49 may be separately applied and of tempered metal. The chutes open into the base 29, as suggested by dotted lines in Figure 9, and the door 20 is unlocked and opened periodically for the collection of the coins accumulated in the base.

The coin-operated motor actuator has its origin in any one of the cranks 45. These, in swinging by the influence of the passage of the coin, exert pressure upon a bar 51 fulcrumed on a pin 52 carried by the motor frame 28, whereby to rock the bar in clockwise direction as viewed in Figure 5. Since the fulcrum is at a medial point, the cranks are of necessity applied from above or below the bar to effect its stated movement. The bar 51 has a hub 51^a from which a detent 53 extends over a side pin 54 of the flywheel spindle 27. Normally, the detent engages the pin and locks the spindle, as shown. However, in the event of the passage of the coin, the rocking of the bar 51 raises the detent 53 off the pin, releasing the spindle so as to permit the motor to run. The rocking bar 51 is normally resisted by a light spring 51^b leading from the base 29, so that the tendency of the detent would be to again fall and lock 130

the flywheel spindle after the event of the passage of the coin. This does not occur, however, due to an element to be presently described which holds the detent in elevated position as soon as the motor has started to run.

The element just referred to is part of the automatic motor stop contemplated in the introductory outline. A clear view of this device is shown in Figure 8. Below the detent 53 a slowly moving motor spindle 54^a receives a disk 55 on whose periphery rides the foot or outward bend 53^a of a downward extension 53^b of the detent. When the motor is not in operation a notch 55^a in the periphery of the disk 55 is adapted to receive the said detent foot 53^a, but when the motor starts, the movement of the disk 55 raises the foot upon the periphery and so maintains the detent in elevated position whereby to permit the flywheel spindle 27 to rotate and the motor to continue running. As described so far, the disk 55 would appear to stop the motor after one revolution, but since this would render the duration of the performance too short, an adjunct is provided wherein the disk is only operative as a stop once in four or more revolutions. The device is in the form of a wheel 56 cut with a series of peripheral cams 56^a and one or more peripheral falls 57^b. The wheel is loosely mounted alongside the disk 55 on a stud 55^b carried thereby, and a spring washer 56^c is interposed between the wheel and the disk to check the tendency of the wheel to turn freely. The peripheral cams 56^a are of ratchet formation and are of even or greater height than the periphery of the disk at the site of the wheel. The latter is positioned opposite the disk notch 55^a, so that when the wheel is turned relative to the disk, its falls 57^b will in turn register with the disk notch. When the motor is in operation the disk 55 rotates in the direction of the arrows in Figure 8, with the detent foot 53^a elevated upon the disk periphery, and each time a wheel cam 56^a strikes the foot 53^a the wheel is moved over a space, while the periphery of the succeeding cam supports the foot and prevents its fall into the notch 55^a. However, when a fall 57^b succeeds the moved cam, it and the notch will receive the foot, and the detent will stop the motor. If the period of operation is to be shortened, the number of falls in the wheel is increased.

The bellows 58, whose interior is indicated in Figure 9, is intended to create a constant supply of air to operate the sounding tube, and receives its motion from a crank 59 operated by the motor gearing. The crank transmits its motion through a pitman 60 to a rocking bar 61 fulcrumed at 61^a to the motor frame, and the rocking bar 61 operates the bellows through a link 62. The bellows comprises a base 63 carried by an extension 64

of the motor frame, a lower pump chamber 65, an upper pump chamber 66 and a storage chamber 67. The partition 68 between the pump chambers is movable vertically, being pivoted at 69 in the base 63, with which the partition 70 between the upper pump chamber and the storage chamber 67 is integral. The top 71 of the storage chamber is pivoted at one end, as indicated at 72. In the operation of the bellows, the upstroke of the partition 68 draws atmospheric air into the chamber 65 through a port 73 in the base 63 by way of a flap or other automatic valve 65^a, at the same time forcing air already in the chamber 66 into the storage chamber 67 by way of a valve 67^a. The air accumulated in the storage chamber 67 passes into the base 63 through a duct 63^a and enters a cavity 63^b in the side of the base which opens upon a plate 74 secured at 75 to said side. On the descending stroke of the partition 68 the evacuation of the pump chamber 66 is relieved by the entrance of atmospheric air into said chamber through a port 66^b in the partition by way of a valve 66^a. In the meantime the air contained in the pump chamber 65 is forced into the storage chamber 67 through a duct 67^b in the base 63 past a valve in the storage chamber. The bellows is thus a double-action and transfusing pump which delivers air to the plate 74 at a uniform rate.

The plate 74 carries, and forms the entrance to the sounding tube 75, which is shown in sectional and separated form in Figure 10. The tube is designed in the manner of the common whistle, having its entrance passage 76 in the plate 74 covered by a valve 77. The body of the tube is fitted with a flattened plug 78 over which the air from the passage 76 passes into a cylinder 75^a, the sound emerging from an opening 79 in the bottom of the tube. The volume of the cylinder 75^a is controlled by the movement of a plunger 80 by a rod 81, so that when the plunger is backed the sound emitted is deep, becoming shrill as the plunger is advanced. A bearing 82 carried by the cylinder 75 and an aperture in the plate 74 serve to guide a rod 83, whose purpose is to bear against the valve 77 at given time for the admission of air to the sounding tube. It will now be seen that, by the proper manipulation of the rods 81 and 83 while the bellows is in operation, it will be possible to sound notes and movements peculiar to birds in song, such as warbles, trills, chirps, runs, calls, etc.

The bird specimens 23 mounted on top of the machine are intended to execute life-like movements in synchronism with the rhythm of the music produced by the sounding tube, so that the impression will be given to the observer that the performers are producing the music. The mechanical factor will thus be in the background while the ob-

server is impressed by the unique performance and attractive setting of the cabinet.

The movements of the bird specimens consist of turning the head 85 in one and the other direction, vibrating the lower section 86 of the bill, and vibrating the tail 87. The specimens are similar and but one will, therefore, require description. The body is a hollow casting, open at the forward end to receive the head 85 and at the rear to project the tail 87. The casting is preferably in two halves, laterally assembled, to receive between them a partition plate 88. On one side of this plate is the head-turning mechanism, while on the other is that for vibrating the bill and tail simultaneously. The head is hollow and has a base plate 89 (see Figure 7) centered on a spindle 90, which is rotatable in a bearing 91 formed from the partition plate 88. The spindle receives a radius arm 92 from which a link connection 93 extends to a bell crank lever 94 rockably carried at 95 by the partition plate. A long wire rod 96 extends down from the free end of the bell crank lever through a foot-extension 84^a of the body 84. It will be seen that moving the wire rod 96 upwardly or downwardly will cause the head 85 to swing in one or the other direction in a manner true to life. Figure 7 illustrates the lower section 86 of the bill as extending inwardly in reduced form, rockably disposed in a standard 97 erected on the base plate 89 of the head. The inner end of the bill shank is linked to a stem 98 which passes through an arcuate slot 99 in the plate to link with the upper end of a rocker bar 100 fulcrumed at 101 alongside the partition plate. Below the fulcrum the rocker-bar is widened to assume the form of the tail 87; and above the fulcrum a long, downwardly extending wire rod 102—companion to the wire rod 96—is linked to the rocker bar. A wire spring 103 directed upon the latter from the fulcrum 101 urges it to draw down on the stem 98 and therefore hold the bill section 86 closed (as shown) and the tail poised during normal conditions. However, when the wire rod 102 is given an upward tug, the result will be the opening of the bill section and drooping of the tail. The object of the linked connections and the arcuate slot 99 is to make allowance in the vibrating mechanism for the head turning action. A covering of plumage is intended for the bird specimens, that they may closely resemble live birds; and their environment is to be a scene of shrubbery with leaves, berries and other artificial effects suggestive of natural scenery. The plumage and effects have not been illustrated in the drawings, as they form no part of the invention and may be varied to suit the designer's fancy or imagination. The specimens and their environment are housed in the glass dome 22, which

while affording a clear view of its contents is a safeguard against the molestation thereof.

The mechanism which operates the control rods 96 and 102 for the bodily movements of the bird specimens and at the same time governs the operation of the sounding tube 75 through the control rods 81 and 83—all in synchronism to render the performance realistic—is illustrated more clearly in Figures 3 and 4. The motor spindle 54^a is formed at its rear end with a stepped hub 105 to fixedly receive a small cam disk 106 and three large ones 107, 108 and 109. The assembly is shown properly grouped in Figures 2 and 3, but for convenience and clearness in Figure 4, the small disk 106 is denoted by dotted lines and the three large disks are separated and some of their connections necessarily broken.

The object of the cam disk 106 is to induce the turning of the birds' heads in the manner described, and the outline of the disk is necessarily formed to render this movement harmonious with the balance of the performance. For one of the heads, the cam disk 106 receives a follower 110 pivoted on a motor frame pin 111, a branch 112 of the follower being linked to the lower end of the wire rod 96 and held down in intimate relation with the cam disk by a motor frame spring 113. For the other wire rod 96 a similar set of parts is used with a somewhat different design, these requiring no additional description except that for identification they are denoted by like reference numerals with the suffix *a*.

The cam disk 107 is intended to vary the pitch of the sounding tube by retracting or advancing the plunger 80 thereof in keeping with the peculiar peripheral contour of the disk, as denoted by deep and shallow notches, inclines and dwells, suitably arranged. The follower in this case is a dog 114 having its hub swiveled on a motor frame pin 115, with a lever 116 extended downwardly to link with the outer end of the plunger rod 81. A motor frame spring 117 draws on the lever 116 to assure the contact of the dog 114 with the cam disk periphery.

The object of the cam disks 108 and 109 is to actuate the sounding tube valve 77 whereby to render the sounding tube operative at intervals corresponding with the peculiar peripheral contours of the disks; and also to vibrate the bill sections and tails of the bird specimens simultaneously with the sounds emitted. Further, the incidents in the peripheral contours of the two disks are arranged in relative alternation, so that but one performer will be in audible and vibratory action at a time. The impression will thus be that the performers are taking turns the silent one only turning its head while

115

120

125

130

the other is in full action. The followers 118 and 118^a of the respective disks 108 and 109 are rockable with hubs on the motor frame pin 115 and are extended downwardly in 5 proximity of a side pin 119 extending from a lever 120 loosely hung from a motor frame support 121, the lower end of this lever being in proximity to the outer end of the valve-actuating rod 83. The follower 118 is 10 extended laterally with a radius arm 122 from which a link 123 connects with one end of a rocker arm 124 fulcrumed on the motor frame pin 111. The opposite end of the rocker arm is linked to the lower end of the 15 corresponding wire rod 102. A more simple connection 124^a ties the follower 118^a to the other wire rod 102; and it will be noted that the lower ends of all the wire rods have elongated loops 125 for a small amount of 20 play as against tendencies toward binding or jamming of the running gear. The followers 118 and 118^a are held to the cam disk peripheries by influence of the wire springs 103 within the bodies of the bird specimens.

25 Recurring to the bellows, it will be noted that a U-shaped spring 126 is provided on the top thereof to press with its lower leg upon the storage chamber 67 and aid the expulsion of air therefrom in the dispensing 30 direction. The upper leg of the spring 126 secures a backing in a notch 126^a above a slot 127 cut in a standard 128, which is attached to the bellows base 63. The slot serves as a guide for the stem 129 of a 35 rocker-valve 130, the latter being normally closed over a port in the top of the storage chamber 67 by the lower leg of the spring 126. The valve 130 is not intended to function during the operation of the machine, 40 and it is therefore held upon its seat more firmly, so as to be ordinarily inoperative. The valve is intended purely for relief purposes when the mechanism is to be operated without the need of the audible factor. In 45 such a case, pressure with one's finger upon the valve stem 129 opens the valve for the air to escape from the storage chamber before it can have effect on the sounding tube.

Since the musical sounds are emitted at 50 the bottom of the cabinet, it is considered best to allow them to escape at that site rather than be carried elsewhere for that purpose, and to this end the floor of the cabinet is cut with an opening 130^a through 55 which the sounds escape to the exterior. This opening is preferably covered with a wire netting 131 to prevent objects from entering the cabinet or ready access to the interior by way of the opening.

60 It is thus seen that a novel machine is provided which, while delivering value for the coin deposited, provides a unique form of entertainment. While the mechanism has been illustrated in preferred form, I am 65 aware that it is capable of many minor

changes and refinements, and I therefore wish to claim all such changes and refinements as coming within the scope and spirit of the appended claim.

I claim:—

A sounding toy comprising a songbird figure having stationary and movable bill sections, a lever to vibrate the movable bill section, a spring attached to said movable bill section to normally urge the same towards said stationary bill section, a cam controlling said movable bill operating lever whereby to impart predetermined characteristics to the vibrations of said bill section, a sounding device, an actuator for the latter, an actuator control operated by said cam and synchronized with the vibrations of the movable bill section, a modulator for the sounding device, and a cam to operate the modulator with a predetermined order of movements to secure variable desired pitch characteristics from the sounding device.

In testimony whereof I affix my signature.
